Primary Examiner — Mark A Goodwin*Assistant Examiner* — Benjamin M Weeks(74) *Attorney, Agent, or Firm* — Andrew F. Young, Esq.; Lackenbach Siegel, LLP(57) **CLAIM**

The ornamental design for a mounting bracket, as shown and described.

DESCRIPTION

FIG. 1 is a front top perspective view of a mounting bracket showing my new design.

FIG. 2 is a front bottom perspective view thereof.

FIG. 3 is a top plan view thereof.

FIG. 4 is a bottom plan view thereof.

FIG. 5 is a left side elevation view thereof.

FIG. 6 is a right side elevation view thereof.

FIG. 7 is a front elevation view thereof.

FIG. 8 is a rear elevation view thereof; and,

FIG. 9 is an illustrative front top perspective view thereof in a use-configuration.

No claim is made to portions which are not shown. The dash-dash lines indicate disclaimed environmental subject matter to which no claim is made. The surfaces are lightly lined for contour.
